UNITED STATES PATENT OFFICE.

EDWARD S. JENISON, OF CHICAGO, ILLINOIS.

SLIDING-RAILWAY.

1,000,009.

Specification of Letters Patent. Patented Aug. 8, 1911.

Application filed January 29, 1910. Serial No. 540,804.

To all whom it may concern:

Be it known that I, EDWARD S. JENISON, a citizen of the United States, residing at Chicago, in the county of Cook and State 5 of Illinois, have invented certain new and useful Improvements in Sliding-Railways, of which the following is a description, reference being had to the accompanying drawings, forming a part of this specification, 10 in which corresponding letters of reference in the different figures indicate like parts.

The object of my invention is to provide a sliding railway which shall be so constructed that a car or train may not only 15 be operated thereon with safety, but started and moved with a minimum of frictional resistance.

I have discovered, as a result of careful study and experiment, that the resistance to 20 movement of one lubricated surface sliding upon another varies in proportion to the area of contact between the two; that said resistance is decreased as the load is increased per unit of area or as the carrying 25 area is decreased until it becomes substantially constant; it being understood that these factors are modified to a considerable degree by the velocity of the moving body as well as by the temperature and lubricity 30 of the lubricating medium.

My invention consists among other things in providing novel means for placing the load upon a freshly or operatively lubricated bearing surface for the purpose of 35 starting it, for reducing and maintaining at a substantial minimum the frictional resistance to the moving body, by varying the area of the carrying or sliding surface, in providing special means for locking the 40 sliding elements to the track, for covering and protecting the track and in novel means for applying resistance to brake the train.

In the drawings, Figure 1 is a transverse vertical sectional view of a portion of a 45 railway track and car embodying the features of my improvement, Fig. 2 is a transverse sectional view of the main elements provided for lifting the car to enable the shoes to be lowered upon a newly lubricated 50 surface, as well as those of the braking mechanism, Fig. 3 is an isometrical view of a portion thereof, Fig. 4 is a like view of one of the frictional shoe elements arranged to coact therewith, Fig. 5 is a like view of a 55 portion of the pneumatic tube mechanism forming a feature of the brake, and lifting

device, Fig. 6 is a longitudinal vertical sectional view, taken upon the line 6—, Fig. 1, viewed in the direction of the arrow there shown, Fig. 7 is a longitudinal vertical sectional view of the adjustable shoe sections, and the sliding cam-faced rod for controlling the bearing thereof, said view being taken upon the line 7—, Fig. 1, viewed in the direction of the arrow there shown, Fig. 60 65 8 is an isometrical view of one of the carrying shoe sections, Fig. 9 is a like view of one of said shoe sections, Fig. 10 is a bottom view of a shoe section showing one form of bearing surface, and Fig. 11 is a 70 like view showing a modified form of bearing surface.

Referring to the drawings, 1, Fig. 1, represents a portion of a suitable framework to which is rigidly bolted a series of brackets 2, 3, to the former of which and its fellows is attached by means of bolts a metal plate 5, having an inwardly and laterally extended flange 6, preferably provided with a groove 7 upon its under face and adjacent to its edge to prevent moisture from passing along said face to the body 5. An L-shaped plate 8 is partially supported by means of the brackets 3, to which it is bolted. The body portion of said plate is 75 80 85 arranged vertically and parallel to that of the plate 5, while a horizontal part 9 is made of sufficient width to considerably overhang said part 5. A depending flange 10 is secured to the edge of the part 9 by 90 means of screws. Interposed between the parts 5 and 8 is a metal member 11 preferably in the form in cross section of an I-beam, which is rigidly attached to the members 5 and 8 by means of bolts 12 and 13 95 passing through the three members; the heads of said bolts being countersunk in the plate 5, while the nuts 14 and 15 are upon the outside. The upper face of the member 11 constitutes the bottom of a 100 groove, the side walls of which are the plates 5 and 8, said face forming a sliding surface for the shoe members hereinafter described.

A portion of the body of a car is shown 105 at 16, Fig. 1, to the bottom of which upon each side is rigidly attached a longitudinal depending plate-beam 17. These beams are rigidly connected by means of transverse vertical plates 18, having flanges 19 formed 110 thereon at right angles thereto. Rigidly attached to the beam-plates 17 by means of

bolts 20, are longitudinal supporting shoes generally designated by 21, between which and each of the plates 17, is interposed spacing plates 22, 23 through which the bolts 20 are passed in addition to the bolts 24; both sets of bolts being extended through the flanges 19 of the cross-plates 18. The carrying brackets 21, shown also in Fig. 8, correspond substantially to the length of the car and each is provided with a laterally extended portion 25, beneath which is formed a relatively large longitudinal groove 26, and a smaller parallel groove 27. A bar 28, Figs. 1 and 7, having a length corresponding substantially to that of the carrying bracket 21, is placed loosely beneath and in engagement with the bearing faces 29 and 30 of the latter, see Fig. 8, said bar having a narrow longitudinal flange 31, Fig. 1, upon its upper edge adapted to fit loosely within the groove 27. Said bar is grooved longitudinally upon its under face, and is provided with a series of oil-holes 32, Fig. 1, throughout its length for the purpose hereinafter stated. A series of shoe-sections generally designated by 33 and 34 respectively, Figs. 1, 6, 7, 9, 10 and 11, are placed beneath the slide-bar 28 and arranged to rest directly upon the upper face of the track member 11. Said sections 30 are placed end to end and are arranged to alternate with each other as shown in Figs. 6 and 7, throughout the length of the main carrying bracket 21. Said sectional shoes are intended to have a free vertical movement independently of each other while at the same time provision is made for locking them to the carrying bracket, so as not only to be moved therewith, but to be lifted from the bearing surface when the main carrying bracket is lifted for the purpose hereinafter stated. In order to accomplish this result, each sectional shoe is provided with upwardly projecting side flanges 35, Figs. 1, 6 and 9, which are identical in each section and each of which is provided with notches 36, Fig. 9, extending downwardly from the upper edge so as to receive projections 37, Figs. 6 and 8, extending outwardly from the part 25 of the main carrying bracket. Cavities 38, Figs. 1 and 8, are formed between the projections 37 in the upper face of the carrying bracket, from the inner ends of which are projected wires 39 adapted to enter holes 40, Figs. 6 and 9, formed in the flanges 35 of the several sections. Said wires are spring tempered to enable them to yield with the slight vertical movement of the sections, and at the same time to lift said sections when the carrying brackets are lifted. The lower face of the sliding bar 28, Figs. 1 and 7, is provided with bearing surfaces 41, upon opposite sides of the central groove, which are located to conform to the respective positions of alternate shoe-sections as clearly shown in Fig.

7, each bearing surface being inclined at opposite ends as shown at 42, in said last named figure. Bearing surfaces 43, Fig. 9, are also formed upon the upper face of each shoe section, which surfaces are inclined at the respective ends as shown at 44, Figs. 7 and 9. A longitudinal groove 45 is formed between the bearing surfaces 43, in which groove is located a series of perforations 46, for passage of oil, also shown in Figs. 10 and 11.

Formed upon the bottom of the shoe-sections 33 are a series of bearing surfaces 47, preferably of circular contour and extending across the entire width of the shoe, while upon the sections 34 are a series of smaller bearing surfaces 48, arranged by preference in a line extending from end to end diagonally across the shoe-section. The bearing surfaces of each alternate section are intended to rest upon the surface of the part 11 and are adapted to be shifted at will by the longitudinal movement of the shifting bar 28, which may be actuated by means of a lever, or otherwise, a distance corresponding to the length of one of said shoe-sections. In practice I prefer to employ compressed air to accomplish this result. In Fig. 6 a cylinder 49 having induction pipes 50 and 51 connected with a source of compressed air, is shown at one end of the car. A piston having a piston-rod 52, is located in said cylinder; said piston rod being connected by means of a rod 53 to the shifting rod 28. Air being admitted to one side of the piston, causes the rod 28 to be moved into the position shown in Fig. 7 with the parts 41 resting upon the shoe-sections 34, thereby enabling the weight of the car to be borne by said sections, while the sections 33 lie beneath the thin portions of the bar and hence are free to be lifted from the track surface. A reversal of the piston serves to shift the parts 41 to bear upon the sections 33 while the sections 34 are free. The object of the inclined portions 42 and 44 upon the shifting bar and sections respectively, being to facilitate this shift.

The track groove, which is covered and protected by the overhanging flange 9, is lubricated with oil throughout its length which oil, as the shoes slide along, is forced into and through the longitudinal groove 26 of the main carrying bracket and thence through the openings in the shifting bar and shoe-sections, to the track, which may thus be kept at all times thoroughly lubricated. The object of the shifting shoe-sections is to enable one set, viz., those having the smaller bearing areas, to be lifted from the track, and the other to be lowered upon a newly lubricated surface to which the load may be transferred to enable the car to be easily started. A further object is to vary the bearing area for different speeds, a compar-

atively large area being required for slow and a smaller one for higher speeds. When the car stands upon the track for a moment the bearing surfaces sink through the lubricant and contact directly with the unlubricated metal; thus rendering it impracticable to start the car because it rests upon the unlubricated surface. But while the car is kept in motion, even at a slow speed, it is easily actuated because the oil cannot escape from between the bearing surfaces and the track quickly enough to enable the two metal surfaces to meet, and hence the shoes are caused to move constantly upon lubricated surfaces.

Having thus described the track and shoe mechanism, I will now consider the means for lifting and lowering the car to enable the load to be transferred from a non-lubricated surface to a newly lubricated surface, which constitutes the most important feature of my invention, and in connection with which I will describe the braking mechanism and means for propelling the car.

The bracket 23, Figs. 1, 2 and 3, is extended above the part 9 and is provided with a horizontal portion 54, also shown in Fig. 6, of substantially the same width as the part 9. Beneath the part 54 is located a series of sectional brake-shoes 55, each of which is provided with an upturned flange 56 upon its outer edge. A series of pins 57 are arranged to project from the inner edge of the shoe into elongated openings 58, formed in the vertical wall of the bracket, Figs. 3 and 4. Bores 59, Fig. 2, are also formed in said brake-shoes for the reception of wire springs 60 which project laterally from the inner face of the bracket. The under face of each of said brake-shoes is intended, when in action, to bear directly upon the upper surface of the part 9, but is normally held out of contact therewith by means of the springs 60.

A longitudinal metal shield, generally designated by 61, has its main vertical member rigidly clamped to the outer face of the part 8 as shown in Fig. 1, by means of a series of clamping members 62 mounted upon the bolts 13. Said clamping members are provided with upwardly extended arms 63, between the upper ends of which and the body of said shield, is interposed wedges 64. Said shield is provided with a top horizontal portion 65, also shown in Fig. 6, and an inner depending portion 66, which portions completely overhang the part 9 throughout the length of the tracks, from which they are sufficiently removed to provide for the intervention of the bracket 23 and the associated braking mechanism,—thereby enabling the part 9 to be protected from accumulations of snow and ice. Located in the horizontal space or cavity between the part 54 of the bracket 23 and the brake-shoes 55 is a flexible pneumatic tube

67, Figs. 1, 2 and 5, formed from india-rubber and any well-known fabric, which tube corresponds to the length of the carrying bracket 23 and is closed at the respective ends by means of a hollow end cover 68, Figs. 5 and 6. One of said end covers is provided with a nipple 69, to which is connected a tube 70 leading to a source of compressed air. When air is forced into the tube 67 the brake-shoes 55 are caused thereby to be depressed against the action of the springs 60, into contact with the surface of the part 9. The extent of the pressure, which may be controlled by the will of the operator, may be varied so as to act merely as a brake, or, when desired, with sufficient force to lift the entire car so as to transfer the load from the carrying shoes 21 to the brake-shoes 55, as hereinafter more fully set forth.

For the purpose of propelling the car I prefer to provide a series of motors located beneath the car body with means for producing tractional action against the web of the track elements. In Fig. 1, I have indicated one of said motors 71, upon the armature shaft 72 of which is mounted in a horizontal plane a traction wheel 73 arranged to bear against the inner face of the web of the track-supporting element 5, immediately beneath the overhanging flange 6, which serves to protect said web from accumulating rain, snow and ice upon its surface. A spring 74, attached in any well known way to the frame of the car, enables the necessary yielding pressure to be brought against the motor through the action of an adjusting screw 75 having lock-nuts 76 thereon.

The operation of my improved device is as follows: Assuming the track to be lubricated throughout its length and the car to be at rest upon the shoe-sections 33, compressed air is admitted to the tube 67, which serves to lift the car, as well as said shoe sections, from the track sufficiently to permit the oil in the track groove to flow beneath the bearing areas 47 of said shoe sections. Power is then applied to move the car, whereupon the air is released from the tubes 67 which permits the load to be shifted to the shoe sections 33 then resting upon the larger freshly lubricated areas, and the car is started with ease before the bearing parts 47 have time to squeeze the lubricant out and again rest upon unlubricated surfaces. As long as the car is kept in motion it may be moved with ease; and inasmuch as the bearing area required for high may be less than that for low speeds, the load may be shifted to the sections 34, as soon as the requisite speed is attained. This may be accomplished by shifting the bars 28 to the relative position shown in Fig. 7, which may be accomplished by admitting compressed air

into the cylinder 49 in such a way as to act upon the piston therein to place the bar under tension, so that the wedge-like portions of the cams may act upon the sections 5 34 to force them down while releasing the sections 33. Should it become necessary to stop the car, the motor is thrown out of action and the car or train allowed to slide until the speed is sufficiently reduced to enable the brakes to be applied. Then the air 10 is slowly introduced to the tube 67, thereby gradually increasing the friction upon the brake-shoes until the entire load is borne thereby. The bar 28 can be then shifted to 15 the position shown in Fig. 6, at which time it may be pushed back without resistance because the weight of the car is sustained by the brake-shoes.

The advantages of my invention are too 20 obvious to require extended mention. It enables the weight of the car as well as the motive power to be greatly reduced, eliminates noise, permits great increase in speed and insures absolute safety against 25 accident by derailment or similar causes.

Having thus described my invention, I claim:

1. In a sliding railway, the combination 30 with a track adapted to be lubricated, of a car having slidable bearings mounted upon said track, and means for shifting said bearings to contact with freshly lubricated track surfaces.

2. In a sliding railway, the combination 35 with a track adapted to be lubricated, of a car having a plurality of slidable bearings, and means for shifting the load from one bearing to another.

3. In a sliding railway, the combination 40 with a track adapted to be lubricated, of a car having slidable bearings mounted upon said track, and means for raising and lowering said car to permit the bearings to descend upon adequately lubricated surfaces.

4. In a sliding railway, the combination 45 with a track or way having lubricated and non-lubricated surfaces, of a car having two sets of sliding elements, one adapted to engage said lubricated and the other said non-lubricated surface, and means for shifting the load from one of said sets of sliding elements to the other.

5. The combination with a sliding railway car, of means for transferring the load 55 from a lubricated to a non-lubricated surface to arrest the movement of the car.

6. The combination with a sliding railway car, of a lubricated way, a protecting shield above said way, and means for lifting the car to transfer the load from said lubricated way to said shield.

7. The combination with a sliding railway car, of lubricated and non-lubricated ways, slidable supports adapted to rest upon 65 said non-lubricated ways, sliding supports

having different bearing areas arranged to rest upon said lubricated ways, and means for shifting the load from said non-lubricated ways to any predetermined number of sliding supports upon said lubricated ways.

8. In a sliding railway, the combination 75 of a car, lubricated and non-lubricated bearing surfaces, respectively, therefor, and means for arresting the movement of the car by shifting a portion of its weight from a lubricated to a non-lubricated surface.

9. In a sliding railway, the combination 80 of a car, lubricated tracks, slidable bearing elements mounted upon said tracks and shields or covers arranged to extend entirely over said tracks, and slidable elements for locking the car to the track and for protecting the latter from the elements.

10. In a sliding railway, the combination 85 of a car, lubricated tracks, slidable bearings mounted upon said tracks, shields or covers arranged to extend entirely over said tracks, and slidable bearings for locking the car to the track as well as for protecting the latter 90 from the elements, slidable elements above and normally out of contact with said shields, and means for causing said sliding elements to be brought into frictional contact with said shields.

11. In a sliding railway having lubricated and non-lubricated ways respectively, the combination of a car, means for shifting the weight thereof from a lubricated to a non-lubricated surface for braking the car, and 100 means for enhancing the capacity of the braking mechanism by increasing the friction upon the non-lubricated surfaces.

12. A sliding railway, in which is combined a car mounted upon a lubricated way, 105 a motor element, a substantially horizontally arranged friction wheel for engaging a friction surface for propelling the car, and means for shielding said friction surface from the action of the elements.

13. A sliding railway in which is combined a car, lubricated and non-lubricated ways, means for shifting the weight of the car from one to the other, and means for covering said respective ways to shield them 115 from the action of the elements.

14. A sliding railway, in which is combined a car with lubricated and non-lubricated ways, a shoe held normally out of contact therewith for engaging the latter, a rigid element located above said shoe throughout its length, a pneumatic tube interposed between them, and means for forcing a fluid into said tube to forcibly expand the same.

15. In a device of the class described, the combination with a main carrying bracket of sectional bearing shoes, a slidable element interposed between said supporting shoe and said bearing, said element having cams 130

or wedges thereon arranged to engage each alternate bearing shoe, and means for shifting said slideable element longitudinally to place the load upon one or another set of bearing shoes.

In testimony whereof, I have signed this specification in the presence of two subscr-

ing witnesses, this 27th day of January 1910.

EDWARD S. JENISON.
